UNITED STATES PATENT OFFICE.

JOHN F. ROSSMAN, OF BLOOMINGTON, ILLINOIS.

FOOT-REST.

No. 905,590.

Specification of Letters Patent.

Patented Dec. 1, 1908.

Application filed September 28, 1908. Serial No. 455,108.

To all whom it may concern:

Be it known that I, JOHN F. ROSSMAN, a citizen of the United States, residing at Bloomington, in the county of McLean and 5 State of Illinois, have invented certain new and useful Improvements in Foot-Rests, of which the following is a specification.

This invention relates to foot-rests, and it has particular reference to an improved adjustable foot-rest adapted to be used in connection with steam and hot-water radiators and with other heating apparatus of a like nature, although the use of the improved foot-rest is by no means limited or confined 15 in this respect.

The invention has for its objects to provide a foot-rest which may be easily and quickly applied in position for operation upon a support, such as would be afforded 20 by the pipes of a radiator of ordinary conventional construction; a further object is to provide for the adjustability of the foot-rest; a further object is to construct a foot-rest including a supporting member which 25 may be readily mounted in position upon the pipes of a radiator and upon which the foot-rest proper may be detachably mounted so as to be capable of being removed and set out of the way when not in actual use; 30 the supporting member being unobtrusive and not unsightly or otherwise objectionable when left in position upon the radiator.

Still further objects of the invention are to simplify and improve the construction of 35 this class of devices.

With these and other ends in view, which will readily appear as the nature of the invention is better understood, the same consists in the improved construction and novel 40 arrangement and combination of parts, which will be hereinafter fully described and particularly pointed out in the claims.

In the accompanying drawings has been illustrated a simple and preferred form of 45 the invention; it being, however, understood that no limitation is necessarily made to the precise structural details therein exhibited, but that changes, alterations and modifications within the scope of the invention may 50 be resorted to when desired.

In the drawings—Figure 1 is a perspective view showing the improved foot-rest mounted upon a radiator in position for operation. Fig. 2 is a perspective view of 55 one of the supporting members, detached.

Fig. 3 is a perspective view of one of the brackets and a portion of the foot-rest, detached. Fig. 4 is a vertical sectional view taken through one of the brackets and supporting members. Fig. 5 is a horizontal 60 sectional view taken on the plane indicated by the line 5—5, in Fig. 4. Fig. 6 is a horizontal sectional view taken on the plane indicated by the line 6—6, in Fig. 4. Fig. 7 is a sectional detail view taken on the plane 65 indicated by the line 7—7 in Fig. 4.

Corresponding parts in the several figures are denoted by like characters of references.

The improved device in its preferred form includes two supporting members 5, 5, each 70 consisting of an elongated body provided at its upper and lower ends with heads or enlargements 6, 7, which are approximately V-shape in horizontal section, being tapered or wedge-shaped in a rearward direction so 75 as to be capable of abutting upon proximate pipes, as 8, 8, of a radiator of conventional construction, a specimen of which has been shown at R in the drawings. The upper head 6 is provided in its upper end thereof with a recess or socket 9, which is preferably 80 of the triangular shape indicated in the drawings; the lower head 7 is provided in the front side thereof with a recess or socket 10, which is preferably of square or rectangular 85 outline. The body of the supporting member 5 is provided intermediate its ends with an aperture 11, for the passage of a securing member such as a bolt 12, which extends rearward between the radiator pipes 90 and is provided with a nut 13 engaging a cross-piece 14, which latter is fitted adjacent to the rear sides of the radiator pipes and is preferably provided with a recess 15 affording a seat for the nut; it will be readily seen 95 by tightening the bolt, the supporting member 5, will be forced in a rearward direction between the pipes of the radiator which will be engaged by the tapering wedge-shaped heads at their upper and lower ends 100 of said supporting member, which latter will thus be securely retained in position owing to the friction between the heads and the pipes. The improved foot-rest device ordinarily calls for the use of two of the supporting members herein described, the same being mounted upon the radiator a suitable 105 distance apart.

The supporting members 5, 5, serve to support a pair of brackets B, B, which may 110

consist of light ornamental castings provided at their upper ends with rearward projecting arms 16, having downward projecting triangular lugs 17, adapted to enter into the recess 9, in the upper heads of the supporting members. These lugs 17, it will be observed, are slightly reduced or rounded at their front corners as indicated at 17^a so as to permit them to readily engage the recesses 9 without danger of binding. Near their lower ends, the brackets B are provided with rearward extending lugs 18, adapted to enter into sockets or recesses 10 in the front sides of the lower heads of the supporting members. Said lower heads may be provided with vertical apertures 19, intersecting the sockets 10, for the passage of keys 20; the lugs 18 being provided with grooves 21, forming seats for the reception of said keys; these keys, however, would not be absolutely indispensable inasmuch as the brackets would be retained in position upon the supporting members by gravity, but as a matter of security the use of the keys is preferred.

The brackets B, B, are preferably formed with ornamental slots or apertures 22 and they are provided adjacent to their upper ends with inclined lugs or ribs 23, having apertures 24, for the passage of bolts 25 equipped with nuts 26, which are accommodated in the slots 22. The two brackets B, B, serve as direct supports for the foot-rest which has been shown as consisting of a strip 26 of suitable length, seated upon the ribs 23, and provided at its edges with downturned flanges 27, engaging the ends of the ribs; said strip 26 being provided with slots 28, affording seats for the heads of the bolts 25, whereby it is adjustably mounted upon the brackets.

From the foregoing description taken in connection with the drawings hereto annexed, the operation and advantages of this invention will be readily understood. The supporting members 5, 5, may be readily mounted in position upon a steam or hot-water radiator of conventional construction, and said supporting members, being practically concealed between the pipes of the radiator, may be permitted at all times to remain in position. The brackets B, B, may be very readily mounted upon the supporting members by simply placing the lugs 17, 18, in engagement with the sockets or recesses 9, 10, and by the insertion of the keys 20, the said brackets will be retained very securely in position. The foot-rest member 26, is finally placed in position upon the brackets; the slots 28, enabling said member to be readily adjusted in the proper and the desired position. It is evident that the height of the foot rest may be regulated by raising or lowering the supporting members 5, 5. The improved device affords a very

convenient and comfortable means of support for the feet of a person seated in front of the radiator. When it is not desired to use the foot-rest, the member 26 and the brackets B, B, are very easily and quickly detached and stored behind the radiator or in some out-of-the-way position; the supporting members 5, 5, being permitted to remain in position upon the radiator as long as may be desired.

As hereinbefore stated, the use of the improved device is not confined to connection with radiators, but it may be utilized in any position that may be found convenient and desirable. It is simple, inexpensive, easily applied and thoroughly efficient for the purpose for which it is provided.

Having thus described the invention what is claimed is:

1. In a device of the class described, a supporting member having wedge shaped heads at its upper and lower ends, the upper head being provided with a vertical recess in the upper end thereof and the lower head being provided with a lateral recess in the front side thereof, in combination with a bracket provided at its upper end with a rearward projecting arm having a downward extending lug and adjacent to its lower end with a rearward extending lug or projection adapted to engage the recess in the front side of the lower head of the supporting member.

2. In a device of the class described, a supporting member having wedge shaped heads at its upper and lower ends, the upper head being provided with a vertical recess in its upper end and the lower head being provided with a lateral recess in the front side thereof and with a vertical aperture intersecting said recess, in combination with a bracket provided at its upper end with a rearward extending arm having a downward extending lug and adjacent to its lower end with a rearward projecting lug having a vertical groove adapted to register with the vertical aperture in the lower head of the supporting member, and a key detachably engaging said groove and aperture.

3. In a device of the class described, a pair of supporting members having wedge shaped heads at the upper and lower ends, the upper heads being provided with vertical recesses and the lower heads being provided with lateral recesses in the front sides thereof, brackets provided at their upper ends with rearward extending arms having downward extending lugs and adjacent to their lower ends with rearward extending lugs, said lugs engaging the recesses in the upper and lower heads of the supporting members with which the brackets are detachably connected, keys extending through the lower heads of the supporting members and engaging the lugs upon the lower ends of the brackets, a strip constituting a foot-rest member sup-

ported upon the brackets and having longitudinal slots and bolts extending through said slots and engaging the brackets.

4. In a device of the class described, the combination with suitable supporting members, permanently secured in position and provided at their upper and lower ends with heads, the upper heads being provided with vertical recesses and the lower heads being 10 provided with lateral recesses in the front sides thereof, of brackets having lugs detachably engaging the recesses of the supporting members, said brackets being pro-

vided near their upper ends with inclined ribs, a strip constituting a foot-rest member 15 supported upon the brackets and having downturned flanges engaging the ends of the ribs, and longitudinal slots; and bolts extending through said slots and engaging the brackets.

In testimony whereof I affix my signature in presence of two witnesses.

JOHN F. ROSSMAN.
